Primary Examiner — Carla Jobe Wright(74) *Attorney, Agent, or Firm* — Birch, Stewart, Kolasch & Birch, LLP(57) **CLAIM**

The ornamental design for a mobile phone case, as shown and described.

DESCRIPTION

FIG. 1 is a front perspective view of a mobile phone case showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof shown in a state of use with an environmental mobile phone and rolled stylus pen.

The dot-dash broken lines in FIG. 8 depict an environmental mobile phone and rolled stylus pen that form no part of the claimed design. The dash-dash broken lines throughout the drawing figures depict portions of the mobile phone case that form no part of the claimed design.

1 Claim, 7 Drawing Sheets(56)
